APPARATUS FOR SEALING CONTAINERS

Paul E. Fischer, Portland, Conn., assignor to Marathon Corporation, a corporation of Wisconsin

Application August 31, 1943, Serial No. 500,705

2 Claims. (Cl. 113—19)

This invention relates to an apparatus for securing an end closure to the end of cylindrical and truncated conical containers.

According to the present invention a device is provided for quickly and easily applying and securely locking and sealing covers upon containers. The apparatus is particularly adapted for applying covers to paper cylindrical containers provided with an upper metal rim portion. The present device secures a complementary metal band provided on a paper cover which is crimped into locking engagement with the metal rim on the container.

The device of the present invention comprises essentially a series of crimping rollers which are carried on bell-crank arms that are actuated so as to cause the rollers to progressively engage the metal band on the cover for crimping or bending it into locking engagement with the metal rim on the container, whereby the cover is attached and sealed to the container.

Other features, advantages and objects of the invention will be more particularly apparent from the following specification and appended drawings, wherein

Figure 1 is a top plan view of the sealing device.

Figure 2 is a sectional view taken on lines 2—2 of Figure 1;

Figure 3 is a side elevational view of one of the crimping rollers in its initial crimping position,

Figure 4 is a similar view showing the crimping roll in its final position,

Figure 5 is a fragmental sectional view of the upper portion of the container and cover in the initial crimping stage,

Figure 6 is a fragmental perspective view of the unattached cover and container, and

Figure 7 is a modified form of construction of the sealing device.

Referring more in detail to the drawings, the apparatus comprises three crimping rollers 10, each rotatably mounted on a shaft 11 which is carried by an outer lever-arm 12 of a bell-crank lever 9 pivoted on shaft 13. The other inner lever-arm of the bell-crank lever is indicated by numeral 14. Shafts 13 are supported in bearings 15 carried on arms 15 of a spider frame-member 16. Frame-member 16 is provided with a central aperture 17 for slidably receiving a stem 18 provided with a stop-head 18' carried by a circular bearing plate 30. A coiled spring 20 is attached at one end to the frame-member and the other end is attached to a lug 21 provided

on the bell-crank lever 9. Frame-member 16 is provided with brackets 25 carrying handles 26. Stem 18 is fixedly attached to bearing plate 30 which is provided with a machined flat cam bearing surface 31 adjacent its outer periphery. Lever-arms 14 of the bell-crank lever 9 are provided with pressure rollers 35 rotatably mounted on shafts 36. Rollers 35 have a convex contour as shown in Figures 3 and 4. Bearing plate 30 is provided with apertures 40 in order to reduce its weight. Bearing plate 30 is channeled at its outer lower periphery 45 for a purpose to be explained later.

The apparatus described is particularly adapted for sealing covers on containers having the construction illustrated in Figure 6, wherein the body of the cylindrical container made of heavy fiberboard and the like is provided at its upper open end with a U-shaped metal rim 51 securely fastened thereto. Metal rim 51 is provided with an outwardly extending beaded portion 52. A cover 53 made of fiberboard is provided with a metal rim or band 54 affixed to its outer periphery having an extending curved flange portion 55. The cover 53 is sealed on the container 50 by the present apparatus so as to assume the final condition illustrated in Figure 4 wherein the curved flange portion 55 of the band 54 on the cover is crimped or bent over into snug engagement with the bead portion 52 of the metal rim 51 of the container. In order to provide a hermetic seal an elastic ring or tube 70 may be interposed between the rim members 54 and 51 as shown in Figure 5.

In sealing covers on containers with the present apparatus, a cover 53 is placed on the open end of a container 50 in the position illustrated in Figure 5. The sealing device is then positioned manually so that bearing plate 30 is positioned over the cover 53, the channeled portion 54 engaging the upper curved flange portion 55 of rim member 54. Light pressure is then applied manually to both handles 26 and at the same time they are rotated one-third of the circumference. Pressure rolls 35 will assume an initial position as illustrated in Figure 3 making contact with the flat bearing surface 31 at the inner periphery thereof, and upon rotation of the spider 30, the convex surface of pressure rolls 35 will make progressive rolling contact with the surface 37 until the position illustrated in Figure 4 is assumed. During this operation the bell-crank levers 9 are rocked on their shafts 13 opposing the normal tension of springs 20 so as to cause rollers 10 to travel progressively from the initial

position shown in Figure 3 to the final position shown in Figure 4. During the travel of the crimping rollers 10 the outer flange portion 55 of the rim member 54 on cover 53 will be crimped inwardly toward the container body 50 and bent into firm engagement with the bead portion 52 of the container rim 51. The shaping of flange portion 55 into the contour complementary with the bead 52 is accomplished by providing rolls 10 with a flat medial portion 8 and an upper inwardly curved or concave portion 7. The initial contact of the rollers 10 with the outermost portion of flange portion 54 is made by the flat medial portion 8 of rollers 10 and the crimping is performed by the inwardly curved portion 7. Upon rotation of the spider member through arms 26 one-third of a revolution, the entire circumference of the rim flange member 54 will be contacted and crimped into locking position. If desired, instead of manual rotation of spider member 16, it may be attached to a motor driven spindle 60 as illustrated in Figure 5. For this purpose spider member 30 is provided with a sleeve 65 which is fixedly attached to spindle 60 by a pin 62.

It is to be understood that this invention is not restricted to the details shown and that numerous changes and modifications may be made in utilizing the significant and essential features of the invention.

I claim:

1. Apparatus for securing the extending peripheral margin of an end closure to the end of a container comprising a spider having spaced arms, a bearing plate slidably carried beneath said spider, said plate being adapted for seating on said end closure, a plurality of bell-crank levers hinged at the extremities of the said spider arms, said bell-crank levers comprising an outer lever-arm and an inner lever-arm, springs for

normally urging said bell-crank levers outwardly, a crimping roller rotatably mounted on each of said outer lever-arms, a pressure roll rotatably mounted on each of said inner lever-arms, said pressure rolls being adapted to rotate and bear on the said bearing plate to pivot the said bell-crank lever inwardly whereby said crimping rolls will move in an arc for crimping said extending peripheral margin of said end closure, and means to move said spider toward said bearing plate so as to bring the crimping rollers into engagement with the peripheral margin of said closure to crimp the same about the end of the container.

15. 2. Apparatus for securing the extending peripheral margin of an end closure to the end of a container comprising a spider having spaced arms, a circular bearing plate slidably carried beneath said spider on a centrally positioned stem, said plate being adapted for seating on said end closure, a flat cam surface adjacent the outer periphery of said bearing plate, a plurality of bell-crank levers hinged at the extremities of the said spider arms, said bell-crank levers comprising an outer lever-arm and an inner lever-arm, a crimping roller rotatably mounted on the said outer lever-arm, a pressure roll rotatably mounted on the said inner lever-arm, said pressure rolls being adapted to rotate and bear on the cam surface of said bearing plate to pivot the said bell-crank lever inwardly whereby said crimping rolls will move in an arc for crimping said extending peripheral margin of said end closure, and means to move said spider toward said bearing plate so as to bring the crimping rollers into engagement with the peripheral margin of said closure to crimp the same about the end of the container.
